United States Patent

Des. 242,195
Patented Nov. 9, 1976

242,195

TENNIS RACKET STAND

Ruth Connors, 3615 Roblar Ave.,
Santa Ynez, Calif. 93460

Filed Jan. 6, 1975, Ser. No. 538,725

Term of patent 14 years

Int. Cl. D6—99

U.S. Cl. D6—151

FIG. 1

FIG. 2

FIG. 3

FIG. 4

FIG. 1 is a perspective view of a tennis racket stand showing my new design;

FIG. 2 is a front elevational view on an enlarged scale, both sides being identical;

FIG. 3 is a side elevational view; and

FIG. 4 is a top elevational view.

I claim:

The ornamental design for tennis racket stand, as shown and described.
